UNITED STATES PATENT OFFICE.

CHARLES FREDERICK LAGANKE, OF HARRISBURG, PENNSYLVANIA,
ASSIGNOR TO ELLIOTT-FISHER COMPANY, OF NEW YORK, N. Y.,
A CORPORATION OF DELAWARE.

COMBINED TYPE-WRITING AND CALCULATING MACHINE.

No. 820,882.

Specification of Letters Patent.

Patented May 15, 1906.

Application filed August 24, 1905. Serial No. 275,580.

To all whom it may concern:

Be it known that I, CHARLES FREDERICK LAGANKE, a citizen of the United States, residing at Harrisburg, in the county of Dauphin and State of Pennsylvania, have invented a new and useful Combined Type-Writing and Calculating Machine, of which the following is a specification.

This invention relates to a combined type-writing and calculating machine of that particular character in which a book type-writer is equipped with one or more computing devices or registers and with operating connections whereby the numeral-keys, besides performing their ordinary functions in connection with the printing of digits, also effect the operation of the computing device or computing devices to compute the total or totals of numbers printed in one or more columns. The primary objects of the present invention are as follows: First, to provide means for positively retaining the transfer-dogs of the computing device in engagement with the number-wheels thereof while the machine is operating in the column to be computed; second, to provide the operating connections of the computing device with a dust case or guard and to equip the computing device with a reading-glass supported in a convenient position at some distance from the digits exhibited at the sight-opening to magnify said digits and facilitate the reading thereof by the operator.

To the accomplishment of these objects the preferred embodiment of the invention resides in the construction and arrangement of parts to be hereinafter described, illustrated in the accompanying drawings, and defined in the appended claims.

In said drawings, Figure 1 is a perspective view of an "Elliott-Fisher billing and adding machine" equipped in accordance with my invention. Fig. 2 is a plan view of the machine. Fig. 3 is a sectional elevation, on a somewhat enlarged scale, of the computing device, a portion of its operating mechanism, and certain associated parts. Fig. 4 is a longitudinal sectional view of the dust guard or case. Fig. 5 is a transverse section of the same, and Fig. 6 is a detail view of the device for insuring the engagement of the transfer-dogs with the number-wheels, and Fig. 7 is a

sectional view of the upper portion of the machine.

Each part is indicated by the same numeral throughout the views.

The Elliott-Fisher billing and adding machine, well known in the art, includes a billing-platen 1, adapted to support the paper and carrying a machine-frame 2, movable lengthwise of the platen for line-spacing and supporting a traveling carriage 3, which sustains the key-operated type-writing mechanism and is movable transversely of the platen for letter-spacing.

At the rear side of the machine-frame 2 is supported a guide-bar 4, upon which is adjustably mounted a computing device or register 5. Within the casing of the computing device is mounted an aligned series of denominational members or number-wheels 6, associated with transfer mechanism which when any wheel has completed nine increments of independent movement will be automatically brought into action to impart a single increment of movement to the wheel of next highest order. This carrying mechanism includes a series of transfer-levers 7, arranged to be thrown down or depressed by projections 8 on the number-wheels.

Mounted in each transfer-lever is a pivoted carrying-dog 9, which engages the next number-wheel to the left of the one which moves the transfer-lever. Thus when a wheel is moving from "9" to "0" the projection 8 thereon engages and swings a transfer-lever 7 to cause the carrying-dog 9 of said lever to advance the next adjacent number-wheel of higher order. These features of the computing device are in common use and appear to require no further description for the purpose of the present disclosure.

The number-wheels 6 are operated by a master-wheel 10, which is mounted on and moves with the carriage 3, being thus presented to successive number-wheels of the computing device as the printing-point of the type-writing machine advances to successive denominational positions in the column being totaled. The master-wheel 10 is operated from the numeral-keys of the type-writer by a series of operating connections, which may be designated as a whole by 11. These connections need not be specifically

described; but it may be stated that, except for the devices which couple said connections to the keys, they are located above the cover-plate 12 of the casing of the carriage 3, as best shown in Fig. 1.

Extending rearwardly from the carriage 3 is a transfer-lever-depressing arm 13, which slightly depresses the transfer-levers to prevent clashing when one or more number-wheels are stopped in the "9" position.

The entire structure described being common to the Elliott-Fisher billing and adding machine of commerce is only disclosed herein in a general way in order that the utility of the structural features to be described, and which constitute the present invention, may be fully understood.

The transfer-dogs 9 are mounted in the transfer-levers 7, as heretofore stated, being pivoted at their upper ends, as indicated at 9^a. In accordance with my present invention each dog is provided with a tailpiece 14, extended upwardly from its upper end and longitudinally curved to present it in concentric relation with the axis of the transfer-lever. Coöperating with the tailpieces 14 is what may be termed a "transfer-dog-retaining bar" 15, having beveled ends 16 (see Fig. 6) and preferably carried by the rear end of the lever-depressing arm 13. As the carriage advances the bar 15 travels across the series of tailpieces 14 of the transfer-dog 9, the relation of the parts being shown at Fig. 3.

It will be noted that the lower end of each transfer-dog extends over a tooth of a number-wheel and that in order for the dog to disengage itself its lower end must swing rearwardly. This movement of the dog is prevented by reason of the fact that the bar 15 obstructs the forward movement of the tailpiece 14, and therefore after the bar has once engaged a tailpiece or arrived in a position opposite the same the dog is incapable of such movement upon its own axis as would permit its disengagement from the number-wheel while the transfer-lever occupies its elevated or normal position. It should be particularly noted, however, that the bar 15 does not prevent such movement of the transfer lever and dog as is necessary to a carrying operation. Such movement of the parts is permitted by reason of the fact that the tailpiece 14 is concentric with the axis of the transfer-lever, and therefore as the lever moves down in the act of carrying the tailpiece of its dog simply moves longitudinally in an arcuate path, the lower end of the dog and the engaged tooth of the number-wheel gradually separating by reason of the divergence of their paths of movement. The bar 15 not only prevents accidental disengagement of the transfer-dogs from the wheels, but actually serves to throw into more effective engagement a dog which may have moved back more or less from the

wheel. Thus the function of restoring a dog to its proper engaging position results from the fact that the tailpiece 14 of the deranged dog will be swung slightly forward and will be engaged by the beveled end 16 of the bar 15 and swung back to its normal position to properly position the dog as the carriage advances from one denominational position to the next.

It should be noted that while the denominational members in the illustrated embodiment of the invention are in the form of wheels that actually carry and display the numbers or digits it is not essential that these members possess either of these characteristics, since the invention resides in the coöperative relation between these members arranged in different denominational positions and the various elements specified regardless of the particular form of the members and equally regardless of whether or not they directly carry and display the digits, it being common in this art to employ denominational members of various forms and equally common to display the digits upon carriers coöperatively related to the denominational members with which the carrying mechanism coacts.

In addition to the mechanism just described for insuring the engagement of the transfer-dogs and number-wheels while the master-wheel is located opposite the register the present invention also contemplates the provision of a dust guard or case 17 for the operating connections of the computing device. This case comprises a pair of pen-end frames 18, rising from the cover-plate 12 adjacent to the opposite ends thereof, celluloid or other transparent walls 19 closing the end frames, and an approximately semicylindrical transparent wall 20 extending between the end frames and inclosing the operating connections of the computing device.

Each of the end frames 18 include an inner member 18^a and an outer member 18^b, the inner member being comparatively stiff and the outer member preferably formed of sheet metal and having a flange 18^c overhanging the inner member and a foot-flange 18^d, which is screwed or otherwise secured to the cover-plate 12. Each end wall 19 has its edges clamped securely between the inner and outer members of an end frame, said members being firmly connected by screws 21 or other retaining devices. The opposite ends of the wall 20 are securely clamped against the outer edges of the inner frame members 18^a by the overhanging flanges 18^c of the adjacent outer members, as clearly shown in Fig. 4.

In order to secure the greatest possible stability of this dust case or guard, and more particularly to prevent spreading of the end frames thereof, said frames are provided with depending lugs 22, screwed or otherwise se-

cured to the end brackets 23 of the computing-device connections. The rear edge of the wall 20 is secured to stiffening-plates 24, notched to accommodate projecting portions 5 of the operating connections or the mountings thereof and having lugs 25 screwed or otherwise secured to the cover-plate 12 or other fixed part, as shown in Fig. 4. The wall 20 of the dust-case is also provided with 10 openings 26, through which project the master-wheel 10 and other parts which necessarily engage and coöperate with elements of the computing device. The front edge of the wall 20 is secured, as by screws 27, to brackets 15 28, rigid with the cover-plate 12. (See Fig. 5.) The walls 19 and 20 of the dust case or guard are preferably, though not necessarily, transparent, as already stated, and while glass, mica, or other suitable material may be used I 20 contemplate forming the walls of celluloid or some similar compound.

By providing the operating connections with a guard or case of the character described the mechanism is kept clean and free 25 from dust, although constantly open to view and readily accessible for repair.

Another feature of the present invention resides in the provision of a reading-glass 29, mounted in a frame 30, secured at the upper 30 end of a standard 31, having a foot 32 disposed at an angle to the standard and resting on the top of the computing device 5. The foot 32 is provided with a bifurcated rear end 33, which engages the shank of a headed 35 screw 34, screwed into the computing-device casing, and in advance of its bifurcated end the foot is provided with a longitudinal slot 35, having an enlarged rear end designed to permit the passage of the head of a second 40 screw 36. By this arrangement it is possible to attach the mounting of the reading-glass to the casing of the computing device or to effect its detachment therefrom without removing the screws, it being simply necessary 45 to move the foot forwardly from the position shown in Fig. 2 in order to bring the head of the screw 36 in coincidence with the enlarged end of the slot 35 when it is desired to remove the mounting or to reverse this operation in attaching the reading-glass to the casing.

When in proper position, the glass 29 is held in an elevated position above the sight-opening 37 of the computing device and is given a 55 sufficient forward inclination to bring the glass in convenient position between the eye of the operator and the digits displayed on the number-wheels 6 before the sight-opening 37. The digits are greatly magnified by 60 the glass, and the reading thereof is thus facilitated.

It is thought that from the foregoing the construction, operation, and advantages of my present invention will be fully understood; but while the illustrated structure ap- 65

pears at this time to be preferable, I desire to reserve the right to effect such changes, modifications, and variations thereof as may come fairly within the scope of the protection prayed.

What I claim is—

1. The combination with a series of denominational members and a series of carrying devices each movable into and out of engagement with a member, of means arranged 70 to engage the carrying devices in succession to insure their engagement with said members.

2. The combination with a series of denominational members, of a series of carrying devices engaging the members, and means 80 presentable to the carrying devices in succession to maintain the engagement thereof with said members.

3. The combination with a series of denominational members, of carrying mechanism therefor including transfer-dogs, and a device movable to engage successive dogs and insure the engagement thereof with said members. 85

4. The combination with a series of wheels, of carrying mechanism including transfer members and transfer-dogs movable on the members, a tailpiece carried by each dog, and means coöperating with the tailpiece to 90 positively resist premature movement of the transfer-dogs to inoperative positions.

5. The combination with a series of denominational members, of carrying mechanism associated therewith and including transfer-levers, pivoted transfer-dogs mounted on the levers and engaging the denominational members, tailpieces extended from the dogs, and means engaging the tailpieces to 95 positively resist disengagement of the dogs from the denominational members prior to the actuation of the transfer-levers.

6. The combination with a series of denominational members, of transfer mechanism associated therewith and including transfer-levers, pivoted transfer-dogs, tailpieces extended from the dogs, and a bar movable across the series of tailpieces and coöperating therewith to prevent premature disengagement of the dogs from the denominational 105 members.

7. The combination with a series of denominational members and a series of carrying devices associated therewith, of an actuator movable to successive members to move 110 the same, and means movable with the actuator to engage successive carrying devices and to prevent premature disengagement thereof from the denominational members.

8. The combination with a series of denominational members, a series of carrying devices therefor including pivoted dogs engaging said members and having tailpieces, an actuator movable to successive members and adapted to move the same, and a retain- 115 120 125 130

ing-bar movable with the actuator and coöperating with the series of tailpieces extending from the transfer-dogs.

9. The combination with a series of denominational members, a series of transfer-levers therefor, dogs pivoted on the levers and having tailpieces concentric with the axis of said levers, retaining means coöperating with the tailpieces of the dogs to prevent said dogs from prematurely moving to their disengaging positions, without interfering with the movement of the dogs when the transfer-levers are operated.

10. The combination with a series of denominational members, of a series of carrying-dogs therefor, an actuator movable to successive members, and a bevel-ended bar movable with the actuator and coöperating with the dogs to insure their engagement with said members.

11. In a combined billing and adding machine, the combination with a computing device, of a traveling carriage, a series of keys and an actuator mounted on the carriage, operating connections intermediate of the actuator and keys, and a casing inclosing the operating connections and having the actuator projected through the wall thereof to engage the computing device.

12. The combination with a computing device, of a plate, operating connections for the computing device mounted on the plate, and a dust guard or case also mounted on the plate and inclosing said operating connections, said guard or case comprising a pair of end frames rising from the plate and each including opposed members, transparent end walls clamped between the members of the

respective end frames, a curved top wall having its opposite edges retained between the members of the frames, and means for securing the opposite longitudinal edges of the top wall to the plate.

13. The combination with a computing device, of a reading-glass therefor, a frame in which the glass is mounted, a single standard supporting the frame, a foot disposed at an angle to the lower end of the standard, and means for detachably securing said foot to the computing device.

14. The combination with a computing device, of a reading-glass therefor, a standard supporting the computing device, a foot located at the lower end of the standard and disposed at an angle thereto, said foot being provided with a bifurcated extremity and with a slot enlarged at one end, and a pair of headed screws carried by the casing of the computing device and designed respectively to be received within the bifurcated end of the foot and within the slot thereof.

15. The combination with a computing device, of a reading-glass therefor, a single standard, a glass-supporting frame and an attaching foot extending in opposite directions from the opposite ends of the standard, and means for detachably securing the foot to the computing device.

In testimony that I claim the foregoing as my own I have hereto affixed my signature in the presence of two witnesses.

CHARLES FREDERICK LAGANKE.
